UNITED STATES PATENT OFFICE

SYLVESTER G. AVERELL, OF NEW YORK, N. Y., ASSIGNOR TO JOHN CHATILLON & SONS,
OF NEW YORK, N. Y., A CORPORATION OF NEW YORK

SPRING SCALE

Application filed June 6, 1929. Serial No. 368,857.

This invention relates to spring scales, and has particular reference to a novel construction for correcting the reading of the indicator on the dial due to the expansion or contraction of the spring material and changes in the stiffness of the springs due to changes in temperature.

A primary object of the invention is to provide a simple, practical and reliable construction which will be accurately responsive to changes in temperature conditions to shift the position of the rack with reference to the pinion, the said rack having teeth pitched at such a predetermined constantly increasing angle from the bottom to the top that as the rack is shifted laterally, it actuates the pinion to correct the indicator errors due to changes in length and stiffness of the springs caused by temperature changes.

20 A further object of the invention is to provide a construction of the type referred to which may be conveniently embodied in a mechanism support of the type disclosed in my co-pending application filed June 6th, 25 1929 Serial No. 368,856, (Case No. 5).

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings, in which:—

Figure 1 is an elevation showing part of the dial and the present improvements also in elevation.

Fig. 2 is a vertical cross-sectional view 40 taken on the line 2—2 of Figure 1.

Fig. 3 is a horizontal cross-sectional view taken on the line 3—3 of Figure 1.

Similar reference characters designate corresponding parts throughout the several figures of the drawings.

In the embodiment of the invention shown in the drawings, the scale mechanism is supported on a hanger designated generally as H, the said mechanism including the loading springs S suspended from the top of the

hanger and supporting the runner A. The dial shaft 1 is journaled as at 2 in the hanger H and carries the dial hand 3 at one end thereof, while the intermediate portion carries the pinion 4 having the hub 5 which prevents longitudinal shifting on the shaft 1.

The pinion 4 meshes with the rack R whose lower end is provided with a shaft 6 extending to opposite sides thereof and loosely mounted in the forked arms 7 of a carrier bar 8 mounted on the runner A. The carrier bar 8 is adapted to be shifted longitudinally of the runner by the adjusting screw 9 which engages the offset portion 10 of the carrier bar, to compress a spring 11 bearing 65 against an offset abutment 12 of the runner through which the threaded shank of the screw 9 passes. By adjusting the screw 9 the relative vertical position of the carrier bar 8 may be adjusted to bring the rack into proper initial engagement with the pinion 4.

In connection with the rack R it will be observed that the same is especially designed to cooperate with a thermostat device designated generally as T. That is to say, the rack R is provided with teeth 13 which are cut on the bias, or, in other words, at a gradually increasing angle to the axis of the pinion 4. The teeth at the point of contact with the pinion at no load are cut at such an angle to the axis of the pinion 4 that lateral movement of the rack across the pinion will correct the zero reading of the indicator for any predetermined range of temperature change preferably from 20° to 100° F. which includes the variations in temperature to which scales are ordinarily subjected. Each succeeding tooth is cut at such a progressively increasing angle that it will actuate the pinion to correct the indicator reading for changes in stiffness of the springs due to temperature changes.

Referring to the thermostat T it will be observed that the same is mounted at its lower end upon a suitable bracket 14 affixed to the carrier bar 8, while its upper end is bifurcated to fit into the reduced portion 15 of the shaft 6 carried by the end of the rack. While the connection between the thermostat and the shaft 6 may assume various forms,

nevertheless, the engagement shown and described is practical and sufficient for illustrative purposes.

For the purpose of maintaining the rack R uniformly in engagement with the pinion 4, a suitable tensioning spring 16 is provided. This spring is preferably a piece of spring wire looped at its lower end as at 17 and having its lower end 18 fitted in the eyes 19 struck out from the body of the hanger N, while the upper end 20 which bears against the rack is provided with an offset portion 21 guided in a suitable opening in one of the down turned sides of one of the intermediate portions of the hanger.

When the scale is made it is designed to operate within certain temperature ranges and the lateral position of the rack with reference to the pinion is initially predetermined so that as the thermostat T bends under changing temperature conditions the shaft 6 of the rack will be moved to the left or right in Figure 2 to bring the rack in position to present more or less of the angular pitch of its teeth into engagement with the pinion. Under high temperature conditions the thermostat T will move to the left and shift the rack in the same direction thus bringing the right side of the teeth 13 in position to engage with the pinion 4. On the other hand, when the scale is subjected to lower temperature conditions the thermostat T will move toward the right and cause a corresponding shift of the rack to bring the low side of the teeth in position to engage the pinion. This arrangement is due to the fact that under higher temperature conditions a lesser movement of the indicating device is required for a given movement of the rack and at lower temperatures a greater movement of the indicating device is required for a given travel of the rack, and this is accomplished by shifting the rack to the left as the temperature rises and to the right as the temperature falls.

From the foregoing it will be apparent that the novel and distinctive feature of the present invention resides in the provision of a thermostatically controlled and laterally shiftable rack having teeth cut on a gradually increasing bias or angle with reference to the axis of the pinion to compensate or correct for the physical changes in the spring due to changing temperature conditions.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. In a spring scale, the combination of an

indicator, an indicator pinion and a rack having its teeth cut at a progressively increasing angle, and a thermostat adapted to automatically change the position of the rack laterally with reference to the teeth of the pinion under changing temperature conditions so as to correct indicator errors due to temperature changes.

2. In a spring scale, the combination of an indicator, and indicator pinion mounted in a relatively fixed position, a laterally shiftable rack having teeth cut at a progressively increasing angle with reference to the teeth of the pinion, and a thermostat operatively connected to the rack and adapted to shift said rack laterally and correct indicator errors due to temperature changes.

3. In a spring scale, the combination of an indicator, and indicator pinion mounted in a relatively fixed position and a laterally shiftable rack having teeth cut at a progressively increasing angle with reference to the teeth of the pinion, and thermostat means for shifting the rack parallel to the axis of the pinion to compensate for the changes in the stiffness of the springs and the changes in the length of the springs due to changes in temperature.

4. In a spring scale, the combination of an indicator pinion and a rack having teeth cut at a progressively increasing angle with reference to the teeth of the pinion, means at the lower end of the rack for slidably mounting the same for lateral movement, and a thermostat device connected to said means.

5. In a spring scale, the combination of an indicator pinion having a relatively fixed mounting and a rack having a plurality of teeth cut at progressively increasing angles with reference to the teeth of the pinion, a runner, a shaft at the end of the rack, means on the runner for engaging the shaft at the end of the rack, and a thermostat device carried by the runner and connected with the said shaft for shifting the same laterally with reference to the teeth of the pinion.

6. In a spring scale, the combination of an indicator pinion and a rack having a plurality of teeth, the tooth initially engaging with the rack being inclined at an angle to correct the zero reading of the indicator and the succeeding teeth being cut at progressively increasing angles to compensate for changes in the stiffness of the springs due to changes in temperature, and a thermostat for shifting the rack laterally with reference to the pinion.

Signed at New York city in the county of New York and State of New York this 27th day of May, A. D. 1929.

SYLVESTER G. AVERELL.
